CLOTHING SHIELD

Filed April 11, 1929

UNITED STATES PATENT OFFICE

JOSEPH ABRAMOFSKY, OF TOLEDO, OHIO

CLOTHING SHIELD

Application filed April 11, 1929. Serial No. 354,398.

This invention relates to clothing shields, and more particularly to a shield to be worn in a coat or the like to protect the garment from perspiration.

5 An important object of the invention is to produce a device of this character which is reversible and includes means whereby it may be secured in position upon the garment in which some of the fastening elements are 10 reversely positionable so that they may be used in either of the positions of the shield and the remainder thereof are so mounted that they may be positioned at points where they will not give any discomfort at all to the 15 wearer.

A further object of the invention is to provide a device of this character having a moisture-proof insulation for insertion between the body and the garment and a moisture 20 absorbent pad which acts to receive and collect the moisture and thus prevent its spreading upon the surfaces of other garments and causing discoloring thereof.

A still further object of the invention is to 25 so construct the device that the pad may be readily removable for cleansing or replacement.

These and other objects I attain by the construction shown in the accompanying drawing, 30 wherein for the purpose of illustration is shown a preferred embodiment of my invention and wherein:—

Figure 1 is a side elevation of a garment shield constructed in accordance with my invention;

Figure 2 is a similar view with one of the sections of the shield folded back;

Figure 3 is an enlarged sectional view 40 through the shield on the line 3—3 of Figure 1.

Referring now more particularly to the drawings, the shield comprises two triangular sections, generally designated at 10 and 11, these sections being made in duplicate and 45 each having one edge thereof concavely curved, as indicated at 12, to correspond to the curvature of the sleeve opening of a garment to which they are to be applied. Each section 10 and 11 comprises a water-proof 50 fabric base 13 which may be either formed

from rubber or rubberized material and which has one side thereof faced as, for example, by a layer of silk or other suitable material, indicated at 14.

At the opposite face, the base sheet 13 has 55 secured thereto about its edges a perimetric flap 15 which lies flatly against the base sheet and provides a central opening 16 preferably having the same general shape as the base sheet.

An absorbent pad 17 is provided which 60 may either consist of a single layer or a plurality of layers of material and which is of slightly greater size than the opening 16, so that when it is placed between the perimetric flap 15 and the base sheet 13, its edges are 65 covered thereby. These covered edges and the perimetric flap have upon confronting faces thereof coacting securing elements. In

the present instance, the pad 17 is disclosed 70 as button-holed at 18 and the perimetric flap as provided with buttons 19. Each perimetric flap adjacent the lower end thereof has 75 pivotally secured thereto a securing element 20, at present disclosed as a safety pin. This pin may be swung about the pivotal connection thereof so that it lies between the flap and the adjacent face of the absorbent pad or 80 lies outwardly of the flap and is positioned to engage with the cloth of a garment to which the shield is being applied. When in the first named position, the securing element lies behind the flap so that it does not come in contact with the person to cause discomfort.

The wall of the base sheet, and of the finishing sheet 14 if applied thereto at a corresponding point, have formed therethrough 85 an opening 21 which is bound or otherwise reinforced at its edges and has pivoted to one of these edges thereof a second securing element 22. This securing element may be moved about its pivotal connection to place it at either side of the base sheet. When disposed at the outer face of the base sheet, it 90 may be engaged with the cloth of a garment and when disposed at the inner face thereof, it is protected by the base sheet against contact with the person of the wearer.

The concaved edges 12 of the sheets are 95 pivotally connected to one another by a 100

connection providing longitudinally spaced openings 23. This connection is at present shown as a cloth strip 24, the edges of which are included in the connections between the base sheet and perimetric flap of each section 5 and in which the openings 23 are formed. At each of the openings, a securing element 25 is pivoted to one of the sections 10 or 11 in such manner that it may be moved through the opening to occupy a position between the sections without regard to the position in which the sections are placed. These securing elements are adapted for engagement with the garment at the sleeve seam and it 10 will be seen that by use thereof in connection with a fastener 20 of one of the sections and a fastener 22 of the other of the sections, the shield will be very firmly held in position.

It will be obvious that the construction 20 employed is capable of a certain range of change and modification without materially departing from the spirit of the invention, and I accordingly do not limit myself to such specific structure except as hereinafter 25 claimed.

I claim:—

1. A reversible shield of the character described comprising two substantially triangular sections each having one edge thereof curved to correspond to the curvature of the sleeve opening of a garment, a pivotal connection between said sections at said edges affording longitudinally spaced openings and securing elements connected to the 30 sections at the openings and movable through the openings to lie between the sections in either position thereof.

2. A reversible shield of the character described comprising two substantially triangular sections each having one edge thereof curved to correspond to the curvature of the sleeve opening of a garment, a pivotal connection between said sections at said edges affording longitudinally spaced openings, securing elements connected to the sections 40 at the openings and movable through the openings to lie between the sections in either position thereof, said sections each including a base sheet of water-proof material,

45 said sections at the lower ends thereof having openings formed therein, and securing elements connected to the sections adjacent the last named openings and movable through said openings to lie at either side of the base sheet.

3. A reversible shield of the character described comprising two substantially triangular sections each having one edge thereof curved to correspond to the curvature of the sleeve opening of a garment, a pivotal connection between said sections at said edges affording longitudinally spaced openings, securing elements connected to the sections at the openings and movable through 55 the openings to lie between the sections in

either position thereof, said sections each including a base sheet of water-proof material, said sections at the lower ends thereof having openings formed therein, securing elements connected to the sections adjacent the last named openings and movable through said openings to lie at either side of the base sheet, said base sheets at corresponding faces thereof having perimetric flaps providing a central opening, an absorbent pad having its edges arranged between the flap and the base sheet and coacting securing means upon said absorbent pad and the inner face of the flap. 70

4. A reversible shield of the character described comprising two substantially triangular sections each having one edge thereof curved to correspond to the curvature of the sleeve opening of a garment, a pivotal connection between said sections at said edges affording longitudinally spaced openings, securing elements connected to the sections at the openings and movable through the openings to lie between the sections in either position thereof, said sections each including a base sheet of water-proof material, 75 said sections at the lower ends thereof having openings formed therein, securing elements connected to the sections adjacent the last named openings and movable through said openings to lie at either side of the base sheet, 80 said base sheets at corresponding faces thereof having perimetric flaps providing a central opening, an absorbent pad having its edges arranged between the flap and the base sheet and coacting securing means upon said absorbent pad and the inner face of the flap. 85
